(57) **CLAIM**

The ornamental design for a massage appliance as shown and described.

DESCRIPTION

FIG. 1 is a front, right, and top perspective view of a massage appliance, showing my new design;

FIG. 2 is a rear, left, and top perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is a detailed view taken from the encircled portion labeled "9" in FIG. 2.

The short-dash and long-dash broken lines in FIGS. 2 and 9 denote the boundaries of the detail areas and form no part of the claimed design. The even broken lines depict portions of the massage appliance and form no part of the claimed design.
